UNITED STATES PATENT OFFICE

101,822

DESIGN FOR A KITCHEN UTENSIL CABINET

Henry M. Robinson, Middlebush, N. J.

Application September 25, 1936, Serial No. 64,999

Term of patent 7 years

To all whom it may concern:

Be it known that I, Henry M. Robinson, a citizen of the United States, residing at Middlebush, in the county of Somerset and State of New Jersey, have invented a new, original, and ornamental Design for a Kitchen Utensil Cabinet, of which the following is a specification, reference being had to the accompanying drawing, forming part thereof.

I claim:—

The ornamental design for a kitchen utensil cabinet as shown.

HENRY M. ROBINSON.
